UNITED STATES PATENT OFFICE.

PHILIP LITTLE, JR., OF MINNEAPOLIS, MINNESOTA, ASSIGNOR TO STRONG-SCOTT MANUFACTURING COMPANY, OF MINNEAPOLIS, MINNESOTA, A CORPORATION OF MINNESOTA.

GRAIN DRYING AND COOLING APPARATUS.

Application filed September 26, 1921. Serial No. 503,208.

To all whom it may concern:

Be it known that I, PHILIP LITTLE, Jr., a citizen of the United States, resident of Minneapolis, county of Hennepin, State of Minnesota, have invented certain new and useful Improvements in Grain Drying and Cooling Apparatus, of which the following is a specification.

In the process of drying grain in all types 10 of grain driers, a great deal of dust, chaff and other refuse material is given off. Some of this material is blown through the drying rooms into the atmosphere, settling on building and grounds; a large part of it is deposited 15 inside the drying rooms and settles on floors, walls, etc., or re-enters the air stream to the drying or cooling apparatus and is deposited on the heating coils, thereby greatly reducing the efficiency of the apparatus and contributing to increased fire 20 hazards and to unsanitary conditions. In a number of grain drying apparatuses now in commercial use, the grain is first heated to 25 evaporate the surplus moisture by forcing a current of heated air through the body of the grain as it passes through a drying chamber, and is thereafter cooled by forcing a cold air stream similarly through the grain while it passes through a cooling chamber. 30 In practice in these apparatuses or machines the greatest amount of dust or refuse material is given off in the section generally known as the cooler, and the object of this invention is to provide means co-operating 35 with the heating and cooling air currents for drawing off and collecting this material and at the same time gathering the dust given off from the heating and discharge chambers and conducting it to a suitable 40 dust collecting apparatus from whence it may be removed in containers or spouted to any desired place.

The invention consists generally in various 45 constructions and combinations, all as hereinafter described and particularly pointed out in the claims.

In the accompanying drawings forming a part of this specification,

Figure 1 is a vertical sectional view 50 through a drying room, showing an apparatus or machine in elevation embodying my invention,

Figure 2 is a vertical sectional view on the line 2—2 of Figure 1;

Figure 3 is a horizontal sectional view 55 on the line 3—3 of Figure 1,

Figures 4 and 5 are similar sections on the lines 4—4 and 5—5 respectively of Figure 1,

Figure 6 is a detail section, showing the separated air chambers of a drier and cooler. 60

In the drawings 10, 10 represent the side walls, 11, 11, the end walls and 12 the floor of the building or structure in which the apparatus is located. As here shown the mechanism is principally supported upon 65 the floor 12. A transverse vertical wall 13 is also shown arranged to separate the building structure into two sections, one section comprising the rooms 14 and 14^a, which contain the drying and air circulating devices 70 and the other section comprising an upper drying room 15 and a lower cooling room 15^a, and containing the grain drying and cooling apparatus.

The drier 16 and cooler 18 consist preferably and essentially of an upright casing shown of rectangular form in cross section and arranged in the rooms 15 and 15^a. The lower end of this casing preferably extends through the floor 12 and is provided with a 80 hopper 48, and an outlet spout 50, and the upper portion of the casing is preferably open and is arranged beneath a hopper 25 to which grain may be supplied through a pipe 25^a. This hopper is located preferably 85 in the upper part of the building structure and the casing is arranged below the hopper so as to receive grain therefrom as illustrated in Figure 6. Vertical transverse partitions 24 extend across the upright casing reaching 90 nearly to the upper and lower ends thereof, the space between these partitions and the end walls of the casing being closed at the upper and lower ends of the walls 24 and being divided into two interior air chambers 95 by the transverse partition 31. These air chambers are preferably located (Figure 6) substantially in the center of the casing whereby a vertical grain passage 19 is formed between each of the partitions 24 100 and the opposing wall of the casing whereby grain entering the upper part of the casing passes downward through the passages 19 into the hopper at the bottom of the casing. A series of horizontal ducts 22 and 23 extend 105 across the grain passages preferably in a horizontal direction from the partition 24 to the outer walls of the casing. These ducts

110

are preferably composed of perforated or screen material and are preferably open at one end and closed at the other, the open ends of the ducts 22 communicating through the walls of the casing with the rooms 15 and 15^a and the open ends of the ducts 23 communicating through the partitions 24 with the air chambers 20 and 21.

A flooring 39 separates the room 15 from the room 15^a bridging the space between the outer walls of the casing and the inner walls of the building structure. This flooring is preferably located substantially on a level with the transverse partition 31. For convenience I also preferably extend this flooring substantially the same level across the other section of the building structure to form a horizontal division between the rooms 14 and 14^a (Figures 2, 3, 6). This flooring is preferably made in the form of a grating, permitting dust that settles on the flooring in the room 15 to pass through the same as hereinafter described.

In the outer walls of the room 15 I preferably provide windows or openings having slats 29 which may be opened to permit the passage of air therethrough (see Figure 6) or may be closed to prevent such passage. Similar openings having slats 30 may be provided for the room 15^a and having slats 57 for the room 14 and slats 56 for the room 14^a.

I may also provide a slatted flooring 39^a extending across the upper part of the room 15, and I may provide an opening having a slat 29^a in the wall of the building structure above this flooring. I also provide a fan 32, which is connected to the air chamber 21 by a suitable pipe connection 33 (Figures 1 and 5). With the slats of the windows of the cooling chamber 15^a open the desired amount, air will be drawn by the fan 32 through the bodies of grain descending through the passages 19. With the arrangement here shown the air from the room 15^a will enter the ducts 23 and then pass through the grain to the ducts 22, and into the air chamber 21 from which it will be drawn through the pipe 33 into the casing of the fan 32. The air from the room 15^a will be cool or unheated and it will act to cool the grain if the same has been previously heated in the upper portion of the casing, as herein-after described, and as this air passes through the grain it will take up and carry through into the chamber and to the fan the dust and light material that is in the body of grain.

Above the drying rooms or in any other convenient place I arrange a collector 34 which may be of any preferred type suitable to separate and collect the dust and refuse matter from dust laden air currents and let the purified air escape. I have shown a collector of the so called "cyclone" type, in

which the dust laden air is blown tangentially into a vertical cylinder and conical chamber near the top thereof through a horizontal inlet pipe 35. A vertical pipe 36, through which the dust laden air from the cooler is elevated to the collector, is connected to the outlet 37 from the fan 32 and to the inlet pipe 35 to the collector. In the cyclone type of collector, the purified air escapes through an opening in the top of the collector and the dust and refuse is collected in the bottom of the cone and is conducted away through a restricted opening or pipe 38 to any suitable destination.

I have here shown a separate fan 26 located in the room 14^a and connected by a pipe 28 extending through the upright wall of the casing 13 and connecting with the air chamber 20 in the upper part of the casing (Figures 1, 2, 3). I prefer to provide suitable heating coils 27 arranged in the conductor 28 which may be enlarged to form a heating chamber, so that air from the fan 26 will be suitably heated and then forced into and through the air chamber 20 and outward through the grain extending through the passages 19 into the chamber 15. The passage of this air through the grain will not only heat the grain but it will remove a considerable portion of the dust 95 therefrom which will pass outward through the duct openings into the chamber 15. If the slats of the windows are open a part of this dust will escape into the outer air through the window, the greater part of it, however, will settle on the slatted floor 39. By closing the slats of the windows all of the dust that is blown through the heater may be confined within the room 15, or these windows may be opened to a greater or less extent so as to permit the escape of a part of the air and a part of it may be permitted to escape through the slatted partition 39^a and the windows 29^a.

In order also to gather and collect the relatively lesser amount of dust released from the drier, I provide the grated floor 39 between the drier and cooler surrounding the grain chamber and reaching to the walls 10 and 11 of the building as hereinbefore stated. Below the grated floor in the room 15^a I arrange hoppers 40 between the walls and grain chambers thereby closing the floor from passing air currents through the grates between the drying and cooling rooms. The hoppers 40 terminate in spouts or pipes 41 and these pipes are connected to trunk pipes 42 leading to the inlet of the fan 32. I prefer for efficiency reasons to connect these trunk pipes by elbows 43 to an inlet in the side of the fan 32 opposite to that of the inlet pipe 33. It will be seen that any dust given off from the drier by the air currents in the room 15 and settling to the floor 39 will gravitate through the 130

grating to the bottom of the hoppers 40 and will be drawn by suction through the pipes 42 to the fan 32, from which it will be conducted to the collector 34. I also prefer to connect one or more short depending pipes 44 to one or both of the trunk pipes 42. Funnels 45 are provided at the lower ends of these pipes near the floor, into which may be swept refuse matter that may be deposited on the floor, and the suction from the fan 32 will carry such matter through the fan to the collector 34. A pipe 46 is also shown connected to the inlet of the fan 32 at 47 and runs below the floor 12 where it is connected to a conical hood 49 arranged over a belt conveyor spout or other means of openly conveying grain for the purpose of collecting any dust that may be given off at this point. This belt conveyor is omitted from the drawings as it forms no part of the present invention. The two fans 26 and 32 are preferably mounted on the same shaft 51 in different housings and driven by a motor 52 through a single belt 53, a motor pulley 54 and a fan shaft pulley 55. Outside air to the drying fan 26 is drawn through the windows 56 in the room 14^a and through the grating and windows 57 in the room 14, and after passing through the heating chamber 28 and drier in the manner above described, is exhausted through the upper windows 29 in the room 15.

I prefer to provide a grating floor 39^a above the room 15 and below the hopper 25 and in the walls 10 and above this floor, windows 29^a are arranged, through which some of the exhaust air from the drier may escape, passing up through the open grates in the floor.

It is obvious from the above that no dust or light refuse can gather at any place in the drier building or rooms, but that all this matter given off in the process of drying the grain will be concentrated by the cooler fan 32 and delivered with the cooling air to the collector 34, from whence it may be disposed of in any suitable manner.

While I have shown the casing of the grain drier and cooler provided with two grain passages, with the air chambers arranged between said passages, I do not limit myself to any particular number of such passages as a single grain passage or more than two can be employed without departing from my invention.

I claim as my invention:

1. In a grain drier and cooler, the combination with an upright casing provided with upper and lower interior air chambers, and grain passages between the walls of the casing and the air chambers, the walls of said casing and the walls of the air chambers being provided with ducts leading through the grain passages, means for forcing heated air into the upper air
2. In a grain drier and cooler, the combination with an upright casing provided with an interior air chamber and grain passages between the walls of the casing and the air chamber, the walls of said casing and the walls of the air chamber being provided with ducts leading through the grain passages, means for drawing cooling air through the descending grain into the lower air chamber, and means for collecting dust taken out of the grain by the passing currents of air. 70
3. In a grain drier and cooler, the combination with an upright casing provided with an interior air chamber and grain passages between the walls of the casing and the air chamber, the walls of said casing and the walls of the air chamber being provided with ducts leading through the grain passages, means for heating the grain as it descends in the upper portion of the grain passages and means for circulating cooling air through grain in the lower portion of the grain passages and through the ducts in the walls of the casing and air chamber, and means for collecting dust taken out of the grain by the passing currents of air. 75
4. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 80
5. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 85
6. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 90
7. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 95
8. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 100
9. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 105
10. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 110
11. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 115
12. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 120
13. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 125
14. In a grain drier and cooler, the combination with an upright casing provided with an interior air chamber and grain passages between the walls of the casing and the air chamber, the walls of said casing and the walls of the air chamber being provided with ducts leading through the grain passages, means for circulating heated air through the grain in the upper part of the grain passages and through the ducts in the walls of the casing and air chamber, and means for collecting dust taken out of the grain by the passing currents of air. 130

with upper and lower interior air chambers and grain passages between the walls of the casing and the air chambers, the walls of said casing and the walls of the air chambers being provided with ducts leading through the grain passages, means for circulating heated air through the grain in the upper portion of the grain passages and through the ducts in the upper air chamber and the corresponding ducts in the casing, and means for circulating cooling air through the descending grain in the lower part of the grain passages and through the ducts in the lower air chamber and the corresponding ducts in the walls of the casing.

7. In a grain drier and cooler, the combination with an upright casing, upper and lower rooms enclosing said casing, upper and lower interior air chambers within said casing, and grain passages arranged between the walls of the casing and the air chamber, the walls of said casing and the walls of the air chambers being provided with ducts leading through the grain passages, means for circulating heated air through the grain in the upper portion of the grain passages and through said upper air chamber and said upper room, means for circulating cooling air through the lower portion of the grain passages and through the lower room and lower air chamber, and means for collecting the dust taken out of the grain by the air currents.

8. In a grain drier and cooler, the combination with an upright casing provided with an air chamber and grain passages between the walls of the casing and the air chamber, groups of ducts opening through the walls of the casing into said grain passages and other groups of ducts opening through the walls of the air chamber into said grain passages, a room enclosing said casing, means for circulating air through said ducts and through the grain in said grain passages, and means for collecting the dust taken out of the grain by the air currents.

9. In a grain drier and cooler, the combination with means for passing heated air through the drier, of means for passing cooling air through the cooler and conducting said air to a collector, a grain discharge opening from said cooler and means for conducting air from said discharge opening to said collector.

10. In a grain drier and cooler, the combination with a fan for forcing heated air through said drier, of an independent fan for drawing cooling air through said cooler, a collector, and means for conducting the cooling air from said independent fan to said collector.

11. In a grain drier and cooler, the combination with means for forcing heated air

through said drier, a room surrounding said drier, a grated floor arranged in said room, hoppers arranged underneath said floor and communicating with said room through said grated floor, a collector and suction means for drawing air from said room through said hoppers and delivering said air to said collector.

12. An apparatus of the class described having drying and cooling rooms and a grain drier and cooler arranged therein and provided with vertical grain passages separated by upper and lower air chambers, said passages having a series of ducts or openings, one group of ducts or openings being open to the drying and cooling rooms and closed to the air chambers, and the other group of ducts or openings being closed to the drying and cooling rooms and open to the air chambers, means for passing heated air through the drying chamber and cooling air through the cooling chamber and means for collecting the dust taken out of the grain by the air currents.

13. An apparatus of the class described having drying and cooling rooms and a grain drier and cooler arranged therein and provided with vertical grain passages separated by an upper air chamber and a lower air chamber, said passages having a series of ducts or openings, one group of ducts or openings being open to the drying and cooling rooms and closed to the air chambers, and the other group of ducts or openings being closed to the drying and cooling rooms and open to the air chambers, means for passing heated air through the drying chamber and cooling air through the cooling chamber and through said ducts or openings, and means for collecting the dust taken out of the grain by the air currents.

14. An apparatus of the class described having drying and cooling rooms and a grain drier and cooler mounted therein provided with vertical grain passages, and upper and lower air chambers and groups of ducts or openings arranged in said grain passages and communicating respectively with said room and said air chambers, means for passing heated air through said drying room and cooling air through said cooling room, means for separating said air chambers, a fan connected with said cooling room and means for collecting the dust taken out of the grain by the air currents.

15. An apparatus of the class described having drying and cooling rooms and a grain drier and a cooler mounted therein provided with vertical grain passages and upper and lower air chambers and ducts or openings in its passages communicating respectively with said rooms and chambers, a floor having openings therein interposed

- between the dryer and cooler, a hopper arranged below said floor in said cooling room, a fan for creating downward currents of air through said hopper, and a dust collector connected with said fan.
16. In a grain drier and cooler, the combination with means for passing heated air through the drier and means for passing a separate current of cool air through the cooler, of means for separating from the air and collecting the dust taken out of the air by the air currents.
17. A grain drier and cooler comprising an upright casing, a grain passage extending through said casing, means for passing heated air through the grain in the upper portion of said air passage, means for passing cooling air through the grain in the lower part of said air passage, and means for separating from the air and collecting the dust taken out of the grain by said air currents.
18. A grain drier and cooler comprising an upright casing, a grain passage extending through said casing, means for passing separate currents of air through the grain in the upper and lower portions of said grain passage, means for heating the air passing through the upper portion of the grain passage and means for separating from the air and collecting the dust taken out of the grain by the air currents.

In witness whereof, I have hereunto set my hand this 20th day of September 1921.

PHILIP LITTLE, JR.
